UNITED STATES PATENT OFFICE

ROBERT L. HAGUE, OF NEW YORK, N. Y., ASSIGNOR TO STANDARD OIL DEVELOPMENT COMPANY, A CORPORATION OF DELAWARE

METHOD AND EQUIPMENT FOR HEAT-INSULATING SHIP SURFACES

Application filed October 21, 1926. Serial No. 143,279.

This invention relates to improvements in the transportation of volatile liquids in vessels, particularly bulk oil carrying vessels. The invention comprises a system for water cooling the deck and sides above the water line, cool water being supplied over substantially all the exposed surfaces adjacent the storage space for the volatile liquid. In this way the evaporation losses from the liquid cargo are minimized.

The invention will be fully understood from the following description taken in connection with the accompanying drawings in which

15 Fig. 1 is a fragmentary perspective view of the forward deck of a tanker;

Fig. 2 is an enlarged side elevation, the view being taken along the line II—II of Fig. 1;

20 Fig. 3 is an enlarged side elevation, the view being taken along the line III—III of Fig. 1.

In the drawings, reference letter A denotes the forward deck of a bulk oil carrying vessel having hatches 1, 2, 3, and 4 opening into the forward storage tanks, which contain volatile liquids. In accordance with my invention, the deck overlying these tanks is divided into compartments by longitudinal and 25 transverse baffle plates denoted respectively by numerals 5 and 6, 6'. These baffle plates serve as weirs or dams to retain water discharged from nozzles 7, 7', and 8, supplied from a pipe system 9, into which sea water 30 is pumped.

The baffle plates have perforations or spill holes 10 at such a height as to form step-wise pools of water. In this way a fair uniformity of depth is maintained over the deck, notwithstanding its curvature. It will be understood that the sea water is discharged more or less centrally of the deck, as shown, and flows through the perforations 10 from each compartment to the next lower compartment. Holes 11 are formed in the bulwarks 12 and through these holes the water from the outer compartments flows down the vessel's sides. A shield plate 13 (Fig. 3) is fitted outboard over the holes 11 to distribute the water in the form of a sheet.

A similar result could be obtained by allowing the water to overflow the tops of the baffle plates, but in the event of the ship's rolling or pitching too great a body of water may leave the pool. This is prevented by the plate area above the spill holes 10. A six inch depth of water is adequate for proper insulation. The influx of water should be sufficient to maintain a fairly rapid flow through the compartments and over the ship's side. The pipe system 9 is provided with valves for the control of the flow of water, and this may be varied as circumstances require.

The baffle plates are secured to the deck by angle-pieces spot-welded or riveted to the plates and deck, or in any other suitable way. The deck surfaces included within the compartments, and the lower portion of the baffle plates, are preferably covered with a suitable water-impervious coating.

A drainage opening 14 is provided in a corner of each compartment. This opening is plugged when the compartments are to be filled. Plugs are fitted in the scuppers, so that all the water discharged on the deck will flow out through the holes 11.

The storage tanks amidship and aft, when filled with a volatile liquid, will be insulated with a water layer or film in the same manner as shown and described for the forward tanks. If it is not desired to flood all the deck compartments, the transverse baffle plates 6' may be imperforate. Then, by closing the proper valves in the pipe system 9, the water flow may be restricted to a limited portion of the deck, for example, the area included between baffles 6 and 6', Fig. 1.

Heretofore it has been considered impractical to transport very highly volatile liquids in bulk oil carrying vessels because of the conduction of heat to the material through the unprotected deck and sides exposed to the atmosphere. The present invention makes it possible to maintain a temperature in the storage tanks not much above the temperature of the water which the vessel is traversing.

As an additional safeguard against loss of volatile liquids and danger from fire, I pre-

fer to connect pipes to the storage tanks to convey all vapors that may be generated in them to a point of discharge high up on the mast, or to a compressor and cooler. Condensate formed is returned to the tanks. The handling of vapors from the tanks in the general manner just referred to is described and claimed in my application for United States patent Serial No. 143,278, filed of even date herewith.

10 Various changes and alternative arrangements may be made within the scope of the appended claims, in which it is my intention to claim all novelty inherent in the invention 15 as broadly as the prior art permits.

I claim:

1. In combination with the deck of a bulk oil carrying vessel, a plurality of baffle plates secured to the deck and arranged longitudinally and transversely to form compartments thereon adapted to retain pools of water, a pipe system supplied with water from outboard and discharging into the inner compartments, drainage means permitting flow 25 from the inner compartments progressively through the outer compartments to the vessel's side, said side having perforations permitting discharge of the water down the side.

2. In combination with the deck of a bulk oil carrying vessel, a plurality of baffle plates secured to the deck and arranged longitudinally and transversely to form compartments thereon adapted to retain pools of water, a pipe system supplied with water from outboard and discharging into the inner compartments, drainage means permitting flow 35 from the inner compartments progressively forward to aft and through the outer compartments to the vessel's side, said side having perforations permitting discharge of the water down the side, and a shield plate fitted over the holes (outboard) to distribute the water in the form of a sheet.

3. In combination with the deck of a bulk oil carrying vessel, longitudinal and transverse baffle plates forming compartments on the deck, the longitudinal baffle plates having perforations spaced at such a height as to maintain a proper water level in each 50 compartment, and means for supplying water to the inner compartments, from which the water flows through the perforations in the successive compartments, the side of the vessel having perforations through which the 55 water from the outer compartments discharges.

4. In combination with the deck of a bulk oil carrying vessel, a plurality of baffle plates secured to the deck and arranged longitudinally and transversely to form compartments thereon adapted to retain pools of water, a pipe system supplied with water from outboard and discharging into certain of said compartments, and drainage means permitting flow 60 from said compartments progres-

sively through other compartments to a point of discharge.

5. The method of cooling a ship's weather deck having portions inclined to the horizontal when the ship is on an even keel, which 70 comprises controllably discharging water upon the higher portions of the deck, and obstructing at a plurality of spaced intervals the water flowing toward the lower portions of the deck, to maintain a layer of water 75 of substantial thickness throughout the extent of the section of deck being treated.

6. The method of cooling a ship's weather deck and adjoining sides, the weather deck having portions inclined to the horizontal 80 when the ship is on an even keel, which comprises controllably discharging water upon the higher portions of the deck, obstructing the water flowing toward the lower portions 85 of the deck at a plurality of spaced intervals to maintain a layer of water of substantial thickness throughout the extent of the section of deck being treated, obstructing the water at the edges of the section to maintain a continuous layer of water at the edges, and 90 continuously flowing the water from the edges down the adjoining sides of the ship in a sheet substantially continuous throughout the extent of the edges.
